MIXER CLOSURE

Chris Gerst, Detroit, Mich., assignor to The Transmission & Gear Company, Dearborn, Mich., a corporation of Michigan

Application January 22, 1952, Serial No. 267,639

9 Claims. (Cl. 259—161)

1

This invention relates to concrete mixers and has particular reference to a closure for the material charging and discharging opening in the end of the mixing drum of a transit mixer.

In accordance with my invention, the mixer is provided with a rotatable mixing drum having an opening in the rear end thereof and a stationary charging hopper having a portion projecting into the drum through such opening. An annular closure is supported for rotation with the drum when in engagement therewith for sealing the opening and is supported for movement away from and toward the drum, the drum being adapted to discharge the material therein through the opening when the closure is moved away from the drum. The novel arrangement herein disclosed for supporting and moving the closure eliminates the necessity of employing an expensive bearing between the closure and the hopper, as is conventional in the art, and which bearing occasions considerable difficulty and expense due to the frequent failure thereof in service.

A principal object of the invention, therefore, is to provide a new and improved closure device for the charging and discharging opening in the mixing drum of a transit mixer.

Another object of the invention is to provide a closure device for a concrete mixer in which relatively rotating parts are provided with a seal therebetween and which seal is so located as to be relatively free from contact with the mix in the drum.

A further object of the invention is to provide a closure for a mixing drum and a novel means for supporting such closure for rotation with the drum and for movement toward and away from the drum.

Other and further objects of the invention will be apparent from the following description and claims and may be understood by reference to the accompanying drawings, of which there are two sheets, which by way of illustration show the preferred embodiment of the invention and what I now consider to be the best mode in which I have contemplated applying the principles of my invention. Other embodiments of the invention may be used without departing from the scope of the present invention as set forth in the appended claims.

In the drawings:

Fig. 1 is a fragmentary and elevational view of a transit mixer embodying my invention.

Fig. 2 is a fragmentary side elevational view of the mixer; and

2

Fig. 3 is a fragmentary sectional view taken along line 3—3 of Fig. 1.

A concrete mixer embodying my invention may comprise a rotatable mixing drum 10 supported on a frame 12 which is adapted to be mounted on the chassis of a truck. The drum 10 has a rearwardly upwardly inclined axis and may be supported at its forward end by a suitable drive arrangement and at the rear end thereof is provided with a track 14 adapted to ride on rollers 16 mounted on brackets 18 which are secured to the mixer frame 12. The rear end of the drum is provided with an opening 20 through which material may be charged into and discharged from the drum. The mixer is of the type wherein the drum is provided with suitable spiral blades (not shown) which are adapted to mix material in the drum upon rotation thereof in one direction, and to effect the discharge of material from the drum upon reverse rotation of the drum.

A material charging hopper 22 is supported in fixed relation to the drum at the rear end thereof and includes a cylindrical portion 24 projecting through the opening 20 in the drum 10 and extending into the drum for a substantial distance so that material from the hopper 22 will be charged into the drum inwardly of the opening 20 therein. The hopper is supported at its upper end by a bracket 26 attached to a frame member 28 which is suitably secured to the mixer frame 12. The hopper is also supported by a pair of arms 30 mounted in sockets 32 which may be made integral with the brackets 18. Adjustable threaded members 34 are pivotally connected to brackets 36 provided on the hopper 22 and have an adjustable threaded connection with arms 30 so that the position of the hopper 22 may be adjusted with respect to the opening in the drum 10.

The drum is provided with a closure member 38 adapted to seal the opening 20 in the drum 10, and the closure 38 is supported for movement toward and away from the drum between the full line position thereof indicated in Fig. 2, at which time the closure 38 is in sealing relation with the drum 10 and rotates therewith, and the dotted line position of Fig. 2, in which position the drum may be rotated so as to effect the discharge of material therefrom through the opening 20. The mixer is provided with a suitable spout 40 arranged below the opening in the drum and adapted to direct material discharged from the drum into a movable supported distributing chute (not shown) with which transit mixers are ordinarily provided.

The closure 38 comprises a substantially flat annular outer ring 41 adapted to seat in sealing relation on a seal member or gasket 42 suitably secured to a drip ring 44 provided on the end of the drum 10. The closure includes an inner ring 46 secured to the closure ring 41 by a series of bolts 48. The cylindrical portion 24 of the hopper 22 has an annular collar 50 suitably secured thereto, such as by welding, and the rounded inner periphery 52 of the inner closure ring 46 is adapted to rotate around and to move substantially axially along the outer periphery of the collar 50.

A resilient annular seal 56 is secured to the portion 24 of the hopper, and the seal member 56 is adapted to be engaged by an annular flange 58 provided on the closure ring 46 when the closure is seated against and rotating with the drum 10. The cylindrical portion 24 of the hopper 22 extends into the drum a substantial distance inwardly of the seal between the closure and the hopper provided by the flange 58 and the resilient sealing member 56 so that the seal is shielded from the dry mix which is charged into the drum through the hopper 22. The seal provided by the member 56 is also positioned and a substantial distance above the normal full load line of the drum 10, which ordinarily is not substantially above the lowermost portion of the opening 20 in the drum, so that the seal is substantially free from contact with the wet mix being agitated within the drum.

A means is provided for shifting the closure toward and away from the drum, and such means comprises a pair of yoke arms 60, each of which may be made integral with or suitably secured to one of the halves of a split ring 61 rotatably connected to closure 38 for moving the latter toward and away from the drum, a pair of operating levers 62 connected to the yoke arms 60, and a means for pivoting the operating levers 62 so as to move the yokes and the closure toward and away from the drum. The two halves of the split ring 61 may be held together by bolts 63. The operating levers 62 are keyed to a rock shaft 64 which is journaled in bosses 66 provided on the brackets 18. A housing 68 is supported by the frame member 28 and one end of the shaft 64 extends into the lower end of the housing 68 and is provided with a sector gear 70 secured thereto. A hand wheel 72 is secured on shaft 74 which has a bevel gear at the inner end thereof adapted to mesh with a bevel gear provided on one end of a shaft 76 journaled in the housing 68, the shaft 76 also being provided with a worm 78 adapted to mesh with the teeth formed on the sector 70 so that rotation of the hand wheel 72 will cause rotation of the rock shaft 64.

Connecting links 80 are pivotally connected at one end to the operating levers 62 and at the other end thereof are provided with adjustable members 82, similar to the adjustable members 34, the adjustable members 82 having a pivotal connection with the yoke arms 60. Rotation of the rock shaft 64 will pivot the levers 62 and therefore move the closure away from or toward the open end of the drum 10. The adjustable connection provided by the members 82 permits proper axial positioning of the closure relative to the drum when the closure is seated thereagainst. The pivotal connection between the yoke arms and the connecting links 80 permits tilting movement of the closure relative to the plane of the opening in the drum so that the

closure may seat against the seal 42 throughout the peripheral extent thereof.

The ring 50 at its upper end is provided with an extension 84 along which the inner periphery 52 of the ring 46 may ride when the closure is moved away from the opening in the drum. As will be seen in Fig. 2, the upper end of the closure, upon movement thereof away from the drum, is adapted to engage the wall 86 of the hopper 22 and thereafter the closure may pivot about the connection between the yokes 60 and adjustable members 82 so as to move into the dotted line position shown in Fig. 2. The inner periphery 52 of the ring 46 is adapted to be supported on the collar 50 provided on the extension 24 of the hopper when the closure is seated against and rotating with the drum 10. As indicated in Fig. 3 a slight clearance is provided between ring 46 and collar 50 so that the closure 20 is adapted to rotate freely about the cylindrical portion 24 of the hopper without binding. While the ring 46 and closure have been illustrated as being rotatable on and slidably along collar 50 and extension 84 thereof, it is apparent that the closure might be supported independently of the collar 50 by means of the shifting mechanism.

The ring 46 is provided with an outwardly opening annular groove 90 which is adapted to receive a flange 92 provided on the split ring 61 so as to have a tongue and groove connection therewith for rotatably supporting the ring 46 and for supporting the same for movement toward and away from the drum.

The ring 61 is provided with one or more passages 94, each of which communicates at the inner end thereof with the groove 90 in closure ring 46 and at the outer end thereof with a grease fitting 96 so that grease may be supplied to the groove 90 for lubricating the same.

While I have illustrated and described a preferred embodiment of my invention, it is understood that this is capable of modification and I therefore do not wish to be limited to the precise details set forth, but desire to avail myself of such changes and alterations as fall within the purview of the following claims.

I claim:

1. In a concrete mixer having a rotatable drum provided with an opening therein through which material may be discharged from said drum, a charging hopper supported in fixed relation relative to said drum and having a cylindrical portion thereof projecting through said opening into said drum for charging material into said drum, an annular closure rotatable about said cylindrical portion of said hopper and axially shiftable relative to said drum and hopper and engageable with said drum about said opening for sealing said opening, said closure being rotatable with said drum when in engagement therewith, means between said closure and said cylindrical portion of said hopper for forming a seal therebetween, a nonrotatable yoke member and an operating lever therefor for shifting said yoke member toward and away from said drum, said closure being connected to said yoke member for movement therewith toward and away from said drum and being rotatably supported thereby.

2. In a concrete mixer having a rotatable drum provided with an opening therein through which material may be discharged from said drum, a charging hopper supported in fixed relation relative to said drum adjacent said opening for charging material into said drum, a closure mov-

able relative to said drum and hopper and engageable with said drum about said opening for sealing said opening, said closure being rotatable with said drum when in engagement therewith, means supporting said closure for rotation and for movement toward and away from said drum, said hopper having a portion extending through said closure, resilient means between said closure and said portion of said hopper for forming a seal therebetween when said closure is in engagement with said drum, said seal being located axially inwardly along said hopper relative to said supporting means for said closure so as to seal said supporting means from the interior of said drum and hopper, means including a nonrotatable yoke member and an operating lever therefor for shifting said yoke member toward and away from said drum, said closure being movable with said yoke member toward and away from said drum and being rotatable relative to said yoke member.

3. Structure according to claim 2 wherein said yoke member is connected to said operating lever so as to permit tilting movement of said closure relative to the plane of said opening in said drum, and means engageable with said closure upon opening movement thereof to cause said closure to tilt in such manner that the lower end thereof moves a greater distance from said drum opening than the upper end of said closure.

4. Structure according to claim 2 wherein said closure and said yoke member are provided with a tongue and groove connection therebetween.

5. Structure according to claim 2 wherein said portion of said hopper is substantially concentric with the axis of rotation of said drum and extends into said drum a substantial distance inwardly of said seal between said closure and said portion of said hopper.

6. In a concrete mixer having a rotatable drum provided with an opening therein through which material may be discharged from said drum, a charging hopper supported in fixed relation relative to said drum and having a portion thereof projecting through said opening into said drum for charging material into said drum, a closure movable relative to said drum and hopper and engageable with said drum about said opening for sealing said opening, said closure being rotatable with said drum when in engagement there-

with, said closure including an outer ring adapted to seat on said drum and an inner ring secured thereto, and means cooperable with said inner ring for moving said closure toward and away from said drum, said inner ring being rotatably and axially movably supported on said portion of said hopper, and resilient means providing a seal between said closure and said portion of said hopper when said closure is in engagement with said drum, said seal being located inwardly along said portion of said hopper relative to said inner ring thereby to seal said inner ring from the interior of said drum and hopper.

7. Structure according to claim 6 wherein said closure is supported so as to be free to tilt relative to the plane of said opening in said drum.

3. In a concrete mixer having a rotatable drum provided with an opening therein through which material may be discharged from said drum, a charging hopper supported in fixed relation to said drum and having a cylindrical portion thereof projecting through said opening into said drum for charging material into said drum, an annular closure movably mounted relative to said drum and hopper and engageable with said drum for sealing said opening, said closure being rotatable with said drum when in engagement therewith and being movable toward and away from said drum, said portion of said hopper projecting through said closure, and resilient means between said closure and said portion of said hopper and forming an annular seal therebetween when said closure is in engagement with said drum, said seal being substantially concentric with the opening in said drum and being located radially inwardly a substantial distance from the edge of said drum defining said opening.

9. Structure according to claim 8 wherein said portion of said hopper extends into said drum a substantial distance inwardly of said seal between said portion and said closure.

CHRIS GERST.
